Des. 184,490
Patented Feb. 24, 1959

184,490

PORTABLE AUTOMOBILE COOLER

Gordon D. Petrie, Phoenix, Ariz., assignor to Wright
Mfg. Company, Phoenix, Ariz., a corporation of Arizona

Application August 11, 1958, Serial No. 52,154

Term of patent 14 years

(Cl. D14—6)

Fig. 1

Fig. 2

Fig. 3

Fig. 1 is a perspective view of the portable automobile cooler showing my design.

Fig. 2 is a plan view of the portable automobile cooler shown in Fig. 1.

Fig. 3 as a side elevational view thereof, the other side not shown being substantially identical; and

Fig. 4 is a front elevational view thereof.

I claim:

The ornamental design for a portable automobile cooler, as shown and described.
